CLAIM

We claim the ornamental design for a chase, as shown and described.

DESCRIPTION

FIG. 1 is a perspective view of a chase;

FIG. 2 is a first side view thereof;

FIG. 3 is a second side view thereof;

FIG. 4 is a first end view thereof;

FIG. 5 is a second end view thereof;

FIG. 6 is a top view thereof; and,

FIG. 7 is a bottom view thereof.

The evenly spaced broken lines depict portions of the article that form no part of the claimed design.

The chase is shown with a symbolic break in its length. The appearance of any portion of the article between the break lines forms no part of the claimed design.
